UNITED STATES PATENT OFFICE.

FREDERICK DRAKE NORMAN, OF SPRINGFIELD, MASSACHUSETTS, ASSIGNOR, BY MESNE ASSIGNMENTS, TO AMERICAN BOSCH MAGNETO CORPORATION, OF NEW YORK, N. Y., A CORPORATION OF NEW YORK.

IMPULSE STARTING MECHANISM.

1,837,322.

Specification of Letters Patent. Patented Apr. 20, 1920.

Application filed September 21, 1917. Serial No. 192,460.

To all whom it may concern:

Be it known that I, FREDERICK D. NORMAN, a subject of the King of England, residing at Green Acres, Long Meadow, 5 Springfield, in the county of Hampden, State of Massachusetts, have invented certain new and useful Improvements in Impulse Starting Mechanism; and I do hereby declare the following to be a full, clear, 10 and exact description of the invention, such as will enable others skilled in the art to which it appertains to make and use the same.

The present invention relates to impulse starting mechanism wherein the driven device is given one or more impulses, each for a fraction of a turn, at a speed considerably higher than the speed of the driving device, and it embodies the use of an impelling spring arranged to be stressed upon relative angular displacement of the driving and driven devices, of locking mechanism for locking the driven device against rotation while the driving device is rotating, 20 and of releasing mechanism for releasing the driven device so that the spring, then stressed, impels the driven device through an appropriate angle. Such mechanism is applicable to various kinds of devices, such 25 as prime movers which are not self-starting, and particularly to magnetos for generating ignition voltages suitable for igniting gaseous mixtures present in the cylinder of the engine with which it is associated when 30 the engine is being turned at low speed in starting.

In devices of this kind, it has been customary heretofore to provide mechanism for rendering the locking mechanism inoperative when the speed of the driving device exceeds a predetermined value. In accordance with my invention, this predetermined value is made variable so that it is possible to adjust the speed at which the impelling 45 movement of the driven member ceases, thus making it possible to use the same mechanism with engines starting into action under their own power at different speeds. In the preferred form of construction described 50 hereinafter, this adjustable feature consists of one or more speed limiting or safety cams carried by the driven member at an ad-

justed position in advance of the locking mechanism.

My invention further comprehends improvements in construction applicable separately or in combination to impulse starting mechanisms which do or do not employ the features hereinbefore mentioned. In the preferred embodiment hereinafter disclosed, a 55 disk, mounted on the driving shaft and carrying angularly-adjustable releasing cams on its periphery, also carries circularly-disposed coiled impelling and buffer springs abutting anchorage posts thereon, and pressure-applying members extending between the impelling and buffer springs project through slots in the flanged rim of the disk on the driven shaft into co-operation with a locking pawl. The parts on the driven shaft and the pressure-applying members are formed into a 60 unitary structure by means of a retaining ring threading the springs, the pressure-applying members and the posts. 65

In the accompanying drawings illustrating the preferred form of my impulse starting mechanism in application, as an example, to a magneto adapted to be driven by the internal combustion engine with which it is associated, Figure 1 is an elevation 70 showing the impulse mechanism in section on line 1--1 of Fig. 2, and showing the magneto partly in section and partly in full view; Figs. 2 and 3 are sections on lines 2--2 and 3--3, respectively, of Fig. 1; Fig. 4 is a 75 section on line 4--4 of Fig. 3; and Fig. 5 is a section on line 5--5 of Fig. 2.

The magneto 1 is of a well known type having an armature 2, mechanical interrupter 3, collector 4, distributor 4', and 80 shaft 5. The driving shaft 6 is supported in a bearing 7 carried by a plate 8 forming the base-plate of the magneto, so as to support the driving shaft in alinement with the magneto shaft, and it carries a pinion 9 85 adapted to be appropriately positioned and driven from the cam shaft of the internal combustion engine with which the magneto is associated for purposes of ignition.

The disk 10 is integral or otherwise fast 90 with the driving shaft 6 and has on its face two diametrically-disposed anchorage posts 11. The circularly-disposed coiled impelling springs 12 abut the anchorage 95

posts, and the stiffer and shorter buffer springs 13 abut the other sides thereof. The diametrically-disposed pressure-applying members 14 extend between the impelling and buffer springs. These parts are formed into a unitary structure by the retaining ring 15 loosely threading the springs, the posts and the pressure-applying members. The retaining ring is split at 16 and its two ends are pinned after the parts are in place. The cam plate 17 is loosely journaled for adjustment. It has two slots 18 for adjusting its angular position, and the screws 19 fasten it in adjusted position on the disk 10. This plate 17 carries diametrically-disposed cams 20 extending over and outwardly of the periphery of the disk 10.

The disk 21 is fast on the magneto shaft 5 and has a flanged rim 22 and a pair of diametrically-disposed slots 23. The pressure-applying members 14 project outwardly of the flanged rim 22 through the slots therein, and are bolted to the disk 21 at 24 to connect them thereto and to the driven shaft 5. The speed limiting or safety cams 25 are mounted on the outer periphery of the flanged rim 22 in advance of the respective pressure-applying members 14 in the direction of rotation, and are secured in adjusted position thereon by means of slots 26 and screws 27.

The pawl 28 is loosely journaled on the stud 29 carried by the stationary member 30. In its operative position, the pawl 28 rides on the outer peripheries of the flanged rim 22 and the disk 10, in position to be lifted by the safety cams 25 and the releasing cams 20, and engaged by the projecting end of the pressure-applying members 14. In its inoperative position, as shown in broken lines in Fig. 2, the pawl is supported by the arm 31 on the other side of the stud 29.

The operation of the impulse starting mechanism will now be described, in connection with an internal combustion engine to be fired by the magneto. The pawl 28 is brought to its operative position on the outer peripheries of the disks 10 and 21 as shown in full lines in Fig. 2, and the driving shaft 6, connected to the crank shaft of the engine in properly timed relation, is turned by cranking the engine.

The arrangement of the pawl and the pressure-applying members 14 is such that they engage to lock the magneto shaft against rotation, just prior to the period of maximum generation of the magneto and the interrupting action of the mechanical interrupter 3. Upon turning the driving shaft further, the impelling springs 12 are stressed, until finally released by reason of engagement of a releasing cam 20 with the pawl 28, the spring then being stressed sufficiently to impel the magneto shaft

through an appropriate angle and at a sufficiently high speed to generate in the magneto a satisfactory igniting voltage. At the end of this impelling movement, the buffer springs 13 arrest the magneto shaft 70 without substantial shock or vibration. The stress of the impelling springs 12 and the coacting faces of the pawl and the pressure-applying members are such that the pawl is usually at the first instance 75 thrown by the releasing cam to its inoperative position, so that if the engine should then start into action under its own power, as is usually the case, the magneto is thereafter driven directly by the engine. If, 80 however, the engine should not start, the pawl is turned back as before into operative position and the operation repeated.

The angle by which the releasing cams 20 normally trail the pressure-applying members in the direction of rotation, is made adjustable so that the relative angular displacements of the driving and driven shafts may be adjusted to provide at all times the requisite stress in the impelling springs at the instant of release. The driving shaft 6 is timed with the crank shaft of the engine by means of the pinion 9, in such manner that in their adjusted position the releasing cams lift the 90 pawl to permit the magneto to be impelled and generate its sparking voltage at the time the piston to be fired thereby is at or near the beginning of its working stroke. In the case of a multicylinder engine, the 100 proper one of the cylinders to be fired is determined in the well known way by the distributor 4.

If, upon starting of the engine, the pawl 28 should not be thrown into inoperative 105 position, or if by inadvertence on the part of the operator, or through accident or for any other reason, the pawl should attain its operative position, it is, as a practical matter, prevented by the safety cams 25, 110 from engaging the pressure-applying members 14 whenever the speed of the driving shaft exceeds a predetermined value, dependent upon the angle by which the safety cams lead the projecting end of the pressure-applying members, the moment of inertia of the pawl, and other considerations, as will be readily understood. Thus, by having the safety cams adjustable in angular position on the disk 21, the speed of the 115 driving shaft at which the locking mechanism is prevented from locking the driven member against rotation may be increased by increasing the lead of the safety cam, and decreased by decreasing that angle. At low 120 speed in starting, the pawl rides smoothly over the safety cams, but in excess of the predetermined higher speed, the pawl is thrown upwardly to such a height that upon 125 again attaining its operative position in 130

contact with the outer peripheries of the disks 10 and 21, the pressure-applying member has passed beyond its position of engagement with the pawl. At still higher speed, one or the other of the safety cams throws the pawl over its center on the other side of the stud 29, whereupon it falls on to its support 31 in permanently inoperative position.

10 Although the impelling springs 12 are not in themselves strong enough to prevent substantial lag of the driven shaft during the periods of maximum generation of the magneto, such lag is prevented during the running period of the engine when the locking mechanism is inoperative as a combined result of those springs and kinetic energy then stored in the rotating parts of the driven member. The disk 21 with its flanged rim 15 22 acts as a fly wheel to materially assist in the attainment of this result.

Having thus described my invention, what I claim is:

1. In impulse starting mechanism, driving and driven shafts, an impelling spring arranged to be stressed upon relative angular displacement of the shafts, locking mechanism for locking the driven shaft against rotation while the driving shaft is rotating, releasing mechanism for releasing the driven shaft, and angularly adjustable means carried by one of the shafts and coöperative with the locking mechanism to prevent locking of the driven shaft when the speed of the driving shaft exceeds the predetermined value for which said adjustable means are set.

2. In impulse starting mechanism, driving and driven shafts, an impelling spring arranged to be stressed upon relative angular displacement of the shafts, locking mechanism for locking the driven shaft against rotation while the driving shaft is rotating, releasing mechanism for releasing the driven shaft, and angularly adjustable means carried by the driven shaft and coöperative with the locking mechanism to prevent locking of the driven shaft when the speed of the driving shaft exceeds the predetermined value for which said adjustable means are set.

3. In impulse starting mechanism, driving and driven shafts, an impelling spring arranged to be stressed upon relative angular displacement of the shafts, locking mechanism for locking the driven shaft against rotation while the driving shaft is rotating, releasing mechanism for releasing the driven shaft, a disk fast on one of said shafts, and a cam angularly adjustable on said disk and coöperative with the locking mechanism to prevent locking of the driven shaft when the speed of the driving shaft exceeds the predetermined value for which the cam is set.

4. In impulse starting mechanism, driving and driven shafts, an impelling spring arranged to be stressed upon relative angular displacement of the shafts, locking mechanism for locking the driven shaft against rotation while the driving shaft is rotating, said locking mechanism including a member fast with the driven shaft, releasing mechanism for releasing the driven shaft, and a cam adjustable in angular position in advance of said member and coöperative with the locking mechanism to prevent locking of the driven shaft when the speed of the driving shaft exceeds the predetermined value for which the cam is set. 8a

5. In impulse starting mechanism, driving and driven shafts, a member fast with the driving shaft and having an anchorage post, a coiled impelling spring abutting the post, a retaining member threading the spring and engaging the post, mechanism constructed and arranged to lock the driven shaft against rotation while the driving shaft is rotating and thereby stress the spring, and means for releasing the driven shaft. 85

6. In impulse starting mechanism, driving and driven shafts, a disk mounted on the driving shaft and having diametrically-disposed anchorage posts, a circularly-disposed coiled spring abutting the posts, a retaining ring threading the spring and the posts, mechanism constructed and arranged to lock the driven shaft against rotation while the driving shaft is rotating and thereby stress the spring, and means for releasing the driven shaft. 95

7. In impulse starting mechanism, driving and driven shafts, a member fast on the driving shaft and having an anchorage post, circularly-disposed coiled and buffer springs abutting the post, a pressure-applying member extending between the impelling and buffer springs, a retaining ring threading said springs and member, mechanism constructed and arranged to lock the driven shaft and the pressure-applying member against rotation while the driving shaft is rotating, and means for releasing said mechanism from locking position. 110 105 115

8. In impulse starting mechanism, driving and driven shafts, a member fast on the driving shaft and having an anchorage post, circularly-disposed coiled impelling and buffer springs abutting the post, a pressure-applying member extending between the impelling and buffer springs and connected to the driven shaft, a retaining ring threading said springs and member, mechanism constructed and arranged to lock the driven shaft against rotation while the driving shaft is rotating, and means for releasing said mechanism from locking position. 120 125

9. In impulse starting mechanism, driving and driven shafts, a disk mounted on the 130

- driving shaft and having diametrically-disposed anchorage posts, circularly-disposed coiled impelling and buffer springs abutting the posts, diametrically-disposed 5 pressure-applying members extending between the impelling and buffer springs, a retaining ring threading the springs and members and engaging the posts, mechanism constructed and arranged to lock the 10 driven shaft and the pressure-applying members against rotation while the driving shaft is rotating and thereby stress the impelling spring, and means for releasing said mechanism from locking position.
- 15 10. In impulse starting mechanism, driving and driven shafts, a disk mounted on the driving shaft and having diametrically-disposed anchorage posts, circularly-disposed coiled and impelling buffer springs abutting 20 the posts, diametrically-disposed pressure-applying members extending between the impelling and buffer springs and connected to the driven shaft, a retaining ring threading the springs and members and engaging 25 the posts, mechanism constructed and arranged to lock the driven shaft against rotation while the driving shaft is rotating, and means for releasing the said mechanism from locking position.
- 30 11. In impulse starting mechanism, driving and driven shafts, a disk fast on the driving shaft and having a releasing cam, an impelling spring carried by said disk and forming a unitary structure therewith, a 35 pressure-applying member fast with the driven shaft and adapted to stress the spring upon relative angular displacement of the shafts, and mechanism for locking the pressure-applying member against rotation 40 while the driving shaft is rotating, said mechanism being released by the releasing cam when the driving and driven shafts have a predetermined angular displacement.
12. In impulse starting mechanism, a 45 unitary driving element comprising a shaft, a disk fast on said shaft and having anchorage posts on its face and a cam portion on its periphery, circularly-disposed coiled impelling and buffer springs abutting 50 said posts, pressure-applying members extending between the impelling and buffer springs, and a retaining ring threading said springs, posts and members; a driven shaft; and mechanism for locking the pressure- 55 applying members and the driven shaft against rotation while the driving shaft is rotating, said cam portion being engageable with said mechanism to release it from locking position.
- 60 13. In impulse starting mechanism, driving and driven shafts, an impelling spring connected to the driving shaft, a disk fast on the driven shaft and having a flange with a slot and a cam portion, a pressure- 65 applying member extending through said slot and adapted to stress the spring upon relative angular displacement of the shafts, a locking member for locking the driven shaft against rotation while the driving member is rotating, and a releasing member 70 for releasing the locking member.
14. In impulse starting mechanism, driving and driven shafts, a disk fast on the driving shaft and having a releasing cam portion, an impelling spring carried by the 75 disk, a disk fast on the driven shaft and having a flange with a slot therein, a pressure-applying member extending between sections of the impelling spring and projecting through said slot, and a pawl engageable with the projecting end of said member to lock the driven shaft against rotation while the driving shaft is rotating and thereby stress the spring, said releasing cam portion being arranged to disengage the 80 pawl from the pressure-applying member.
15. In impulse starting mechanism, driving and driven shafts, a disk fast on the driving shaft and having diametrically-disposed releasing cam portions, impelling and 90 buffer springs carried by the disk, a disk fast on the driven shaft and having a flange with diametrically-disposed slots therein, pressure-applying members extending between the impelling and buffer springs and projecting through said slots, and a pawl adapted to engage the projecting end of either of said members to lock the driven shaft against rotation while the driven shaft is rotating and thereby stress the impelling 95 springs, said cam portion being arranged to disengage the pawl from respective ones of the pressure-applying members.
16. In impulse starting mechanism, driving and driven shafts, a disk fast on the 105 driving shaft and having diametrically-disposed releasing cam portions, impelling and buffer springs carried by the disk, a disk fast on the driven shaft and having a flange with diametrically-disposed slots therein 110 and a cam portion leading the slot in the direction of rotation, pressure-applying members extending between the impelling and buffer springs and projecting through said slots, and a pawl adapted to engage the 115 projecting end of either of said members to lock the driven shaft against rotation while the driven shaft is rotating and thereby stress the impelling springs, said releasing cam portions being arranged to disengage 120 the pawl from respective ones of the pressure-applying members.
17. In impulse starting mechanism, driving and driven shafts, a disk fast on the driving shaft and having a releasing cam portion, an impelling spring carried by the disk, a disk fast on the driven shaft and having a flange with a slot therein and cam portions each leading the nearer slot in the direction of rotation, a pressure-ap- 125 130

- plying member extending between sections of the impelling spring and projecting through said slot, and a pawl engageable with the projecting end of said member to lock the driven shaft against rotation while the driving shaft is rotating and thereby stress the spring, said releasing cam portion being arranged to disengage the pawl from the pressure-applying member.
- 16 18. In impulse starting mechanism, a driving shaft, a driven shaft, an impelling spring connected to the driving shaft, a limiting cam fast on the driven shaft, a pressure-applying arm fast with the driven shaft and adapted to stress the spring upon relative angular displacement of the shafts, a locking member engageable with the pressure-applying arm to lock the driven shaft against rotation while the driving shaft is rotating, and a releasing cam fast on the driving shaft to disengage the locking member from the pressure-applying arm, the pressure-applying arm trailing the limiting cam and leading the releasing cam in the direction of rotation.
19. In impulse starting mechanism, a driving shaft, a driven shaft, a member fast with the driving shaft, an impelling spring arranged to be stressed upon relative angular displacement of the shafts, locking mechanism for locking the driven shaft against rotation while the driving shaft is rotating, and angularly adjustable releasing means carried by said member for releasing the locking mechanism at the angular displacement of the shafts predetermined by the setting of the releasing means.
20. In impulse starting mechanism, a
- driving shaft, a driven shaft, a disk fast with the driving shaft, an impelling spring 40 arranged to be stressed upon relative angular displacement of the shafts, locking mechanism for locking the driven shaft against rotation while the driving shaft is rotating, and a cam angularly adjustable on 45 the disk to release the locking mechanism at the angular displacement of the shafts predetermined by the setting of the adjustable cam.
21. In impulse starting mechanism, a 50 driving shaft, a driven shaft, a disk fast with the driving shaft, an impelling spring arranged to be stressed upon relative angular displacement of the shafts, locking mechanism for locking the driven shaft 55 against rotation at more than one angular position, and cams carried by said disk and being arranged to release the locking mechanism when the driven shaft is at the respective locked positions, said cams being 60 rigidly connected for like angular adjustment relatively to said disk.
22. In impulse starting mechanism, a driving shaft, a driven shaft, a disk fast with the driving shaft, an impelling spring 65 arranged to be stressed upon relative angular displacement of the shafts, locking mechanism for locking the driven shaft against rotation at more than one angular position, a plate loosely journaled in the 70 driving shaft and having releasing cams for releasing the locking mechanism, and means for fastening said plate to said disk at angularly adjusted positions.

In testimony whereof I affix my signature. 75
FREDERICK DRAKE NORMAN.
